GAME APPARATUS

Thomas M. Bains, Jr., San Francisco, Calif.

Application March 20, 1945, Serial No. 583,710

6 Claims. (Cl. 273—120)

1

My invention relates to game apparatus.

An important object of the invention is to provide a game apparatus which may be operated with different degrees of success depending upon the skill of the player.

A further object of the invention is to provide a game apparatus having a variable speed ball, which renders the game interesting and attractive to play.

A further object of the invention is to provide a game apparatus wherein the speed of a rolling ball is varied by the grade, gauge or parallel or nonparallel relation of the rail track rails, as well as the coefficient friction between the ball and the track surface.

A further object of the invention is to provide simple and cheap adjustable means for supporting the track rails at the desired grade or inclination.

A further object of the invention is to provide means to catch the ball after it has traveled through one of the track units, and feed the same to any selected track unit.

Other objects and advantages of the invention will be apparent during the course of the following description.

In the accompanying drawings forming a part of this application and in which like numerals are employed to designate like parts throughout the same,

Figure 1 is a longitudinal section taken on line 1—1 of Figure 2.

Figure 2 is a plan view of the same.

Figure 3 is an enlarged central vertical enlarged longitudinal section through the ball holding receptacle and associated elements.

Figure 4 is a plan view of the ball holding receptacle and associated elements.

Figure 5 is a perspective view of the ball holding receptacle and the ball transfer receptacle.

Figure 6 is a perspective view of one end of the casing,

Figure 7 is a perspective view of one track unit,

Figure 8 is a transverse section taken on line 8—8 of Figure 2,

Figure 9 is an enlarged side elevation of the ball,

Figure 10 is a central vertical section through the same,

Figure 11 is a central vertical section through a modified ball, and

Figure 12 is a central horizontal section through the ball of Figure 11.

In the drawings, wherein for the purpose of illustration is shown a preferred embodiment of

2

my invention, the numeral 10 designates a casing, having a top 11, preferably formed of transparent material. The top has a forward end 12 and a rounded corner 13, as shown. The end 12 has a central vertical slot 14, leading at its lower end into a horizontal slot 15, having short vertical slots 16 arranged beneath the same and in communication therewith. The vertical slots 16 correspond in number and arrangement to the track units to be described. At its upper end, the vertical slot 14 leads into an upper horizontal transverse slot 17, leading into elongated inclined or longitudinal slots 18, corresponding in number and arrangement to the vertical slots 16.

15 The numeral 19 designates a transfer or feed receptacle, having an incline front face or end 20. A shank 21 is rigidly secured to the rear end of the receptacle 19. This shank is square in cross section and will slide in the slots but will not turn therein. The shank 21 has a collar 22 rigidly secured thereto and is provided with a handle 23, as shown.

20 Arranged within the casing 10 and extending longitudinally thereof are a plurality of track units 24. Since I have shown six notches or slots 16 there will be six track units. These track units are arranged in vertical planes and extend longitudinally within the casing 10. Each track unit comprises superposed tracks which are inclined. The uppermost track comprises rails 25, which are spaced and inclined downwardly in a rearward direction. These rails also diverge rearwardly. The forward ends of the rails 25 are held within openings 26 formed within a spreader-plate 27. The rear ends of the rails 25 are held within openings 28 formed in a spreader-plate 29. The next pair of lower rails 30 have their ends held within openings 31 of the spreader-plate 29 and the rails 30 are inclined downwardly in a forward direction and diverged forwardly and have their ends held within openings 32 of a spreader-plate 33. The next lower pair of rails 34 are inclined downwardly in a rearward direction and have their forward ends held within openings 35 of the spreader-plate 33 and their rear ends held within openings 36 of a spreader-plate 37. The next lower pair of rails 38 are inclined downwardly in a forward direction and diverged forwardly and their forward ends are held within openings 39 in a spreader-plate 40, while their rear ends are held within openings 41 in the spreader-plate 37. The spreader-plates in each vertical group have pairs of openings 42, for receiving flexible elements or cords 43. This permits each spreader-plate to

30 35 40 45 50 55

be conveniently vertically adjusted upon the cords to vary the inclination of the pairs of rails. The spreader-plate will be held in the adjusted position by frictional engagement with the cords. The rear cords 43 are suitably anchored at their upper and lower ends within the casing 10, while the rails 25 and 38 rest upon horizontal rods 42', and the ends of the forward cords 43 have knots 43'. Any suitable means may be employed to hold the pairs of tracks in place.

Arranged at the forward discharge end of each lower-most pair of rails 38 is a stationary holding receptacle 44, having an inclined rear wall 45. The front end of this receptacle is open and the receptacle is provided at its open end with vertical guides 46, receiving a vertical slide 47, urged upwardly by a spring 48. The bottom 49 of the receptacle 44 is inclined, as shown. The slide 47 is moved downwardly by an extension or lift 50, formed upon the inclined side 20 of the receptacle 19.

Circuit closing means is arranged within the receptacle 44, including a stationary contact 51 and a movable contact 52 which is biased open. These contacts are insulated from each other and are connected with wires 53 and 54. The wire 53 has a light bulb 55 connected therein and a source of current 56 is connected in the wires 53 and 54, as shown.

Extending across the casing 10 near its forward end and beneath the pair of rails 25 is a rock shaft 57, varying upstanding fingers 58, projecting between and above the rails 25 in the several pairs. The rock shaft 57 is turned in one direction by a spring 59, and is turned in the opposite direction by a crank 60 arranged exteriorly of the casing.

Adapted to travel upon the tracks in each set is a ball 61. The diameter of the ball is such that when it approaches or reaches the spread end of the rails, it will drop through the space between these rails and be caught upon the adjacent ends of the rails next beneath the same. The ball will travel a short distance up such next rails, due to inertia and will then reverse itself and run down the rails to drop through the lower spread end of the same.

The ball 61 is hollow and is preferably thin and light and may be formed in hemispheres 62, the meeting edges of which overlap and are secured together, forming a slight annular rib 63, arranged upon its inner surface. I have found that the conventional ping pong ball may be used for this purpose. Arranged within the hollow ball 61 is a spherical weight 64, such as a lead buckshot. The weight 64 is, of course, free to roll in any direction within the hollow ball 61.

The operation of the game apparatus is as follows:

If there are six track units there would be six balls 61. In the beginning, all balls would be within the stationary holding receptacles 44. The player now grasps the handle 23 and shifts the shank 21 in the slot 15 until the shank is over the selected depending slot 16, depending upon the selected track unit. The handle 23 is now depressed and the lip 50 of the transfer receptacle 19 depresses the slide 47 while the receptacle 19 is being lowered. The ball 61 rolls from the receptacle 44 into the receptacle 19. The slides of the other receptacles are in no way actuated and only the selected ball can be caught in the receptacle 19, which is shiftable for use with all of the receptacles 44. The handle 23 is now raised so that the shank 21 passes into the

horizontal slot 15 and is moved therein to enter the vertical slot 14 and is then moved into the horizontal transverse slot 17. The shank 21 is shifted in the slot 17 to bring it adjacent to the selected slot 18. Any slot 18 may be selected to receive the shank 21. When the shank 21 enters the longitudinal slot 18, the transfer receptacle 19 is tilted to a vertical position and the ball 61 will roll down the inclined end 20 and be discharged upon the take-up end of the rails 25 of the selected track unit. The ball rolls down these rails by gravity and passes between the lower spread ends of the same and falls upon the next lower rails 30. Due to inertia, the ball will roll up the rails 30 for a short distance and will then reverse its direction of travel and roll down the rails 30 by gravity. In a corresponding manner the ball passes from the discharge end of each pair of rails to the take-up end of the next lower pair of rails and after passing thru the entire track unit, is discharged into the receptacle 44.

When rolling down the pair of track rails, the ball is, of course, turning upon its axis in a plane of rotation. The interior rib 63 may be arranged in a plane at a right angle to this plane of rotation, or in a plane parallel with the plane of rotation, or in planes at varying angles between these two extreme positions. When the internal rib 63 is in a plane at a right angle to the plane of rotation of the ball 61 it will offer the maximum interference with the free rotation of the weight or ball 64. This ball is heavier than the hollow ball 61 and causes the ball 61 to rotate in a jumpy or irregular manner. The disturbance is at the maximum when the weight 64 is rolling over the internal rib 63. When the hollow ball 61 has its internal rib 63 in a plane parallel with the plane of rotation of the ball 61, the action of the weight 64 is reduced to the minimum. It is thus seen that the weight will control to a considerable extent the action and speed of rotation of the ball 61, and the action of the weight is in turn adjusted or regulated by the position that the internal rib 63 has with respect to the plane of rotation of the ball 61. When the ball 61 is introduced into the transfer receptacle 19 and fed by this receptacle to the upper end of the selected track unit, the relative position of the internal rib 63 is entirely a matter of chance. Hence the speed of rotation and the manner of rotation of the ball when used with the receptacle 19 introduces an element of chance into the playing of the game apparatus.

The fingers 58 serve to hold all of the balls 61 in the starting position when fed to the intake end of the track units, and all balls are released at the same time by swinging the crank 60 downwardly, which retracts the fingers 58. The several balls thus run down the track units, and as these balls roll irregularly, their travel is interesting and exciting, and may depend wholly upon chance, or the skill of the players in arranging the balls upon the tracks. Further, the speed of the balls may be controlled by adjusting the grade of the tracks.

I also contemplate using the track units without enclosing them in the casing 10, or otherwise providing access to the upper take-up ends of the track units. This will enable the player to hold the ball in his hand and adjust the internal rib 63 with respect to the plane of rotation of the ball as applied to the track. By this means the rolling action of the ball will depend largely upon the skill of the player. Further, when ac-

cess can be readily had to the track units, the player can vary the grade or inclination of the rails, by vertically adjusting or sliding the spreader-plates upon the cords 43. The openings in the spreader-plates may be varied for changing the divergence of the rails.

In Figures 11 and 12, I have shown a modified form of ball for use with the track unit 24. This ball includes an outer hollow ball 65, which is thin and light. The numeral 66 designates a housing, which is flat, circular, and extends diametrically of the ball 65. This housing has a spiral passage 67 extending from the center 68 and terminating at the periphery or circumference of the ball. The spiral passage 67 holds a traveling weight 69, which is preferably mercury, altho a solid ball could be used. When the ball 65 rotates clockwise, the mercury 69 travels toward the outer end of the passage 67, thus increasing the eccentric load of the ball. This will cause the ball to rotate in an irregular manner. When the mercury reaches the outer end of the passage 67 it will move back and forth for a limited extent, during the clockwise rotation of the ball, thus further rendering such rotation irregular. When the ball rotates counter-clockwise, the mercury travels to the inner end of the passage 67 and the mercury is then concentric with the ball and the load is concentric. The ball will then rotate in a regular manner. The mercury will travel in the passage 67 with the maximum freedom when the passage 67 is in a plane parallel with the plane of rotation of the ball 65, and when the passage 67 is in a plane at a right angle to the plane of rotation of the ball, the mercury will have only a limited movement. The ball 65 may be used with the receptacle 19 and will then introduce a chance element into the playing of the game apparatus, or this ball may be used with the accessible track unit and then the player may manipulate the ball when applying the same to the track, regulating the plane of the spiral passage 67 with respect to the plane of rotation of the ball.

It is to be understood that the forms of my invention herewith shown and described are to be taken as preferred examples of the same, and that various changes in the shape, size, and arrangement of parts, may be resorted to, without departing from the spirit of my invention or the scope of the subjoined claims.

Having thus described my invention, what I claim is:

1. In game apparatus, a casing having a cover and end, the end having a lower horizontal slot and a plurality of depending vertical slots, the end having a vertical slot leading into the horizontal slot, the casing being provided near the cover and the end with a horizontal slot leading into the vertical slot and the casing also having a plurality of longitudinal slots leading into the second named horizontal slot, ball receiving track units arranged within the casing and corresponding in number and arrangement to the longitudinal slots, a holding receptacle at the discharge end of each track unit, a slide for each holding receptacle, a transfer receptacle having a part to engage and depress the slide, and a handle secured to the transfer receptacle and having a shank to slide within the slots.

2. In game apparatus, a track unit comprising supporting flexible elements, spreader-plates having apertures to receive the flexible elements and vertically adjustable thereon, said spreader plates

having openings, and pairs of superposed inclined rails having their ends held within the openings of the spreader plates and adapted to receive a ball or the like thereon.

5. In game apparatus, a plurality of horizontally spaced track units arranged within the casing, each track unit having discharge and intake ends, a casing receiving the track units and having a continuous guide means leading to the discharge ends of the horizontally spaced track units and to the intake ends of the horizontally spaced track units, a transfer receptacle arranged within the casing, and a handle secured to the receptacle to shift it and operating within the

10 15 guide means and extending to the exterior of the casing.

4. In game apparatus, a plurality of horizontally spaced track units arranged within the casing, each track unit having an upper intake end and a lower discharge end, a casing receiving the horizontally spaced track units, said casing having slot means including a part arranged near the upper intake ends of the track units and a part arranged near the lower discharge end of the track units, a transfer receptacle arranged within the casing, and a handle attached to the transfer receptacle to move it and extending through the slot means to the exterior of the casing, the handle being guided in its movement by the slot means.

5. In game apparatus, a plurality of track units arranged side by side, each track unit including intake and discharge ends arranged at different elevations, supporting means for the track units, said supporting means having a continuous guide, parts of the guide being arranged near the intake and discharge ends of the track units, a rolling element receiving transfer receptacle, and means to move the receptacle and having its action controlled by the guide means.

6. In game apparatus, a plurality of track units arranged side by side, each track unit being vertically inclined and having an upper intake end and a lower discharge end, means to support the track units, a ball receiving transfer receptacle, a continuous guide means having a part arranged near the upper intake ends of the track units and a part arranged near the lower discharge ends of the track units, means to move the receptacle and having its operation controlled by the guide means, and means to hold balls in the starting position upon the intake ends of the track units and to substantially simultaneously release the balls.

55 THOMAS M. BAINS, JR.
